MASSACHUSETTS.

SAND-SPREADING DEVICE.

1,083,224.

Specification of Letters Patent. Patented Dec. 30, 1913.

Application filed April 7, 1913. Serial No. 759,393.

To all whom it may concern:

Be it known that we, FRED W. SNOW and ASA B. CUMMINGS, citizens of the United States, residing at Bryantville and South Hanson, respectively, in the county of Plymouth and State of Massachusetts, have invented certain new and useful Improvements in Sand-Spreading Devices; and we do hereby declare the following to be a full, clear, and exact description of the invention, such as will enable others skilled in the art to which it appertains to make and use the same.

The present invention relates to sand spreading devices or machines and is designed particularly for use in spreading sand upon cranberry bogs.

The object of the invention is to provide a sand spreading machine by which sand can be spread rapidly and evenly over a cranberry bog without injury to the bog.

With the above object in view, the present invention consists in the devices, combinations and arrangements of parts hereinafter described and claimed, the advantages of which will be obvious to those skilled in the art from the following description.

A sand spreading machine embodying the several features of the present invention in their preferred form is illustrated in the accompanying drawing in which;

Figure 1 is a plan view of the machine; Fig. 2 is a view in side elevation of the machine; and Fig. 3 is a detail sectional view taken on the line 3—3 of Fig. 1.

The machine, as illustrated, comprises two troughs 1 in which the sand is placed. These troughs are rigidly connected together and extend in parallel relation to each other. The two troughs are supported by a supporting wheel 4 located between the troughs, the axis 5 of the wheel being arranged at right angles to the troughs so that the troughs can be moved along longitudinally over the surface of the bog. The troughs are also provided with supporting legs 6 at their rear ends and these legs are so proportioned with relation to the diameter of the wheel 4 that when the legs are resting on the ground the troughs are supported in a substantially horizontal position. At the rear ends of the troughs, handles 7 are provided by means of which the rear ends of the troughs can be lifted to raise the legs 6 from the ground and bring the troughs

into an inclined position to cause a flow of sand toward the front or delivery ends of the troughs. To spread the sand in an even sheet over the ground as the troughs are wheeled along, a fluted roller 8 is provided at the delivery end of each trough. The rollers 8, as best shown in Fig. 2, extend above the bottoms of the troughs and form stops to prevent the sand from running out of the troughs too quickly or in too large quantities when the troughs are inclined. Means are provided for rotating the rollers 8 in a direction to raise the sand from the troughs and deliver it over the tops of the rollers. As illustrated in the drawing, this means consists of a wheel 9 rigidly secured to the shaft 10 carrying the rollers 8. The wheel 9 is smaller than the wheel 4 and is so arranged that it can be brought into contact with the ground or raised therefrom. When in contact with the ground the wheel 9 is revolved and the sand is distributed evenly by the rollers 8. To stop the delivery of sand the handles 7 are lowered sufficiently to remove the wheel 9 from the ground.

To regulate the flow of sand to the rollers 8, a controlling device is provided in each trough consisting of a shaft 11 provided with radially projecting pins 12, which shaft is located in the troughs a short distance to the rear of the roller 8. The shaft 11 is rotated in a direction opposite to the direction of rotation of the rollers 8 by intermeshing gears 13 and 14 on the shafts 10 and 11 respectively.

As shown in Fig. 1, the two troughs are separated a distance equal to the width of one of the troughs. By arranging the troughs in this manner it is possible to sand two strips of bog simultaneously, and to cover the whole bog without spreading two layers of sand on any portion of the bog. The manner in which the machine is used to sand a bog will be readily understood if it is considered that the bog is divided up into a series of strips, each the width of one of the troughs 1. In starting the sanding operation the wheel 4 will be caused to traverse the middle of strip number two, and thus strips one and three will be sanded. The next trip of the wheel 4 will be along strip number three, and thus strips numbers two and four will be sanded. The next trip will be along strip number six, and thus strips five and seven will be sanded, and on the

next trip strips six and eight will be sanded. In like manner the other strips are sanded until the entire surface of the bog is covered.

5. The preferred embodiment of the present invention having been specifically described, what is claimed is:—

10. 1. A sand spreader having, in combination, a trough, a fluted roller at the delivery end of the trough extending above the bottom of the trough, and means for rotating the roller in a direction to raise the sand from the trough and deliver it over the top of the roller.

15. 2. A sand spreader having, in combination, a trough, a fluted roller at the delivery end of the trough extending above the bottom of the trough, means for rotating the roller in a direction to raise the sand from the trough and deliver it over the top of the roller, and a device for controlling the flow of sand to the roller.

20. 3. A sand spreader having, in combination, a trough, a fluted roller at the delivery end of the trough extending above the bottom of the trough, a supporting wheel for the trough, and a driving wheel for the fluted roller arranged to be brought into engagement with the ground by tipping the

25. 4. A sand spreader having, in combination, a trough, a fluted roller at the delivery end of the trough extending above the bottom of the trough, a supporting wheel for

30. 35. the trough, a driving wheel for the fluted roller arranged to be brought into engagement with the ground by tipping the trough, and a rotary device for controlling

the flow of sand to the roller driven by the driving wheel.

40. 5. A sand spreader having, in combination, a trough, a fluted roller at the delivery end of the trough extending above the bottom of the trough, means for rotating the roller in a direction to raise the sand from the trough and deliver it over the top of the roller, a shaft provided with radially extending pins arranged to control the flow of sand to the roller, and means for rotating the shaft in a direction opposite to the direction of rotation of the roller.

45. 6. A sand spreader having, in combination, a trough, a wheel and legs for supporting the trough in substantially horizontal position, a fluted roller at the delivery end of the trough extending above the bottom of the trough, means for inclining the trough to cause a flow of sand toward the roller, and means for rotating the roller in a direction to raise the sand from the trough and deliver it over the top of the roller when the trough is in inclined position.

50. 7. A sand spreader having, in combination, two troughs, a supporting wheel located between the troughs with its axis at right angles to the troughs, a sand delivering roller at the front end of each trough, means for inclining the troughs to cause a flow of sand toward the rollers, and means for rotating the rollers.
